D. C. Jordan,

Door Lock,

№ 62,753.

Patented Mar. 12, 1867.

Inventor;

David C. Jordan

United States Patent Office.

DAVID C. JORDAN, SR., OF BROOKLYN, NEW YORK.

Letters Patent No. 62,753, dated March 12, 1867.

IMPROVEMENT IN DOOR LOCKS.

The Schedule referred to in these Letters Patent and making part of the same.

TO ALL WHOM IT MAY CONCERN:

Be it known that I, DAVID C. JORDAN, sr., of the city of Brooklyn, Kings county, and State of New York, have invented a new and useful Improvement in Door Locks; and I do hereby declare that the following is a full and exact description thereof, reference being had to the accompanying drawings, and to the letters of reference marked thereon.

The nature of my invention consists in the combination of a revolving disk, two or more bolts, catch, and stop, in such a manner as to lock the door, with two or more bolts, by means of a key. The peculiar construction of the catch prevents the lock from being "picked" without great difficulty.

To enable others skilled in the art to make and use my invention, I will now proceed to describe its construction and operation.

Figure 1 is a view of one side of the lock.

Figure 5 is a view of the reverse side.

Figure 2 is a view of the same side, the plate *a* being removed.

Figure 3 is a view of the internal arrangement of the lock.

Figure 4 is a sectional drawing of the lock and key.

A is a metallic case, constructed in the usual way. *B* is an ordinary lock-bolt; *b b* are three rods extending out from the three other edges of the lock, and have screw-threads at their outer ends to attach bolts to; these bolts extend across the door, so as to lock into sockets fastened to the jambs, top, and side, and also into one at the bottom of the door. The inner ends of the rods are fastened to the disk *C*; this disk is rotated by means of a key, *K*, or knob, *F*, and the movement of this disk throws the bolts into their sockets, or draws the bolts from their sockets, as may be desired. The bolt *B* is moved by means of a pin, *r*, fastened to the disk *C*, which works in a slot in the bolt. There is a lever, *d*, figs. 3 and 4, hung so as to turn at *W*, fig. 4; this lever surrounds the spindle of the lock *t*, and has a pin, *g*, at one end of it. The pin *g* just fits into a hole in the disk *C*, (see fig. 3,) and is kept pressed either into this hole or into the hole *s*², fig. 3, by means of a spring (not shown in the drawing.) This pin *g* prevents the disk from being rotated, acting as a catch. A portion of the spindle *t* is made hollow, and has a smaller spindle, *m*, inserted in the hollow. Through the small spindle *m* is a pin, *o*, which extends through a slot in the large spindle, and rests upon the lever *d*. When the pin *g* is pressed in the hole in the disk, the outer end of the hollow spindle and the outer end of the small spindle are even with each other. The spindle *t* extends through the casings of the lock, and has a knob, *F*, attached to its end; this spindle is held in its position by the socket *u*, through which it passes. There is a plate, *a*, figs. 4 and 5, secured to the case, through which is the key-hole. On the inner side of this plate a stop, *s*, is fastened. *K* is a key, having a hole in its shaft, made to fit the spindle *t*. A pin, *l*, of the same diameter as the small spindle *m*, is fastened in the key. There is also another pin extending out from the guard, or lever, of the key, which fits into the hole *s*² in the disk. The figs. 1, 2, and 5, are drawn to a scale of one-half the size of the figs. 3 and 4.

The operation of the lock is as follows, to wit: The key is inserted into the key-hole when the bolts are out, and is then turned till it comes in contact with the stop *s*; it is then pushed into the lock, the pin on the guard of the key entering the hole *s*² in the disk; and the pin *l*, pressing on the small spindle *m*, will force the end of the lever *d* against its spring, thereby releasing the pin *g* from its hole in the disk. When the key is pressed in to its full limit, the guard *p* can pass under the stop *s*, and by turning the key, the disk will be revolved, thereby drawing in the bolts; the door can then be closed, and locked by turning the key; it will then be locked at the top, bottom, and at both sides. The door may be unbolted from the inside by pressing on the outside end of the lever *d*, (thereby releasing the pin *g* from its hole in the disk,) and turning the knob *F*.

Having now described my invention, what I claim as my invention, and desire to secure by Letters Patent, is—

The combination of the bolts, revolving disk, and catch lever, substantially as described, operating as herein specified, for the purpose set forth.
